Primary Examiner — Jennifer Rivard(74) *Attorney, Agent, or Firm* — Ronald T. Sia; Kevin C. Johnson; Steven W. Miller**CLAIM**

The ornamental design for a razor, as shown and described.

DESCRIPTION

FIG. 1 is a perspective view of a razor of the present invention; FIG. 2 is a top view thereof; and, FIG. 3 is a bottom view thereof.

The dashed broken lines are directed to the environment and are for illustrative purposes only and form no part of the claimed design.
